US00D673800S

(12) **United States Design Patent**
Young

(10) **Patent No.:** **US D673,800 S**
(45) **Date of Patent:** **** Jan. 8, 2013**

(54) **MATTRESS BED ENCASEMENT**

3,749,301 A 7/1973 Peckar
3,775,526 A 11/1973 Gilmore
3,822,426 A 7/1974 Mistarz
3,848,283 A 11/1974 Ikeda

(75) Inventor: **Julian Young**, Zebulon, NC (US)

(Continued)

(73) Assignee: **Nomaco Inc.**, Zebulon, NC (US)

(**) Term: **14 Years**

(21) Appl. No.: **29/398,647**

(22) Filed: **Aug. 3, 2011**

(51) **LOC (9) Cl.** **09-09**

(52) **U.S. Cl.** **D6/606**

(58) **Field of Classification Search** D6/382,
D6/583, 595–601, 604–607; 5/99.1, 630,
5/632, 633, 636, 637, 639, 644, 646, 652,
5/655, 655.3, 655.9, 690, 691, 696, 702,
5/705, 706, 716, 717, 718, 727–730, 740;
D21/698, 803, 809; D24/183

See application file for complete search history.

(57) **CLAIM**

The ornamental design for mattress bed encasement, as
shown and described.

DESCRIPTION

FIG. 1 is a top perspective view of a mattress bed encasement;
FIG. 2 is a top view of the mattress bed encasement in FIG. 1;
FIG. 3 is bottom perspective view of the mattress bed encasement in FIG. 1;
FIG. 4 is a bottom view of the mattress bed encasement in FIG. 1;
FIG. 5 is a front view of the mattress bed encasement in FIG. 1;
FIG. 6 is rear view of the mattress bed encasement in FIG. 1;
and,
FIG. 7 is a left side view of the mattress bed encasement in FIG. 1, and the right side is identical thereto.

1 Claim, 7 Drawing Sheets
